(57) **CLAIM**

The ornamental design for a dual tilt handles pull down faucet body, as shown and described.

DESCRIPTION

FIG. 1 is a perspective view of a dual tilt handles pull down faucet body showing my new design;
FIG. 2 is another perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof;
FIG. 9 is an enlarged view selected from FIG. 1 thereof; and,
FIG. 10 is an enlarged view selected from FIG. 2 thereof.
The broken lines throughout the drawing figures depict portions of the dual tilt handles pull down faucet body that form no part of the claimed design.
